US00D766044S

(12) **United States Design Patent** (10) **Patent No.:** **US D766,044 S**
Davis et al. (45) **Date of Patent:** **** Sep. 13, 2016**

(54) **DISPENSER**

(71) Applicant: **Tablecraft Products Company**,
 Gurnee, IL (US)

(72) Inventors: **Glenn R. Davis**, Delray Beach, FL
 (US); **David R. Burnside**, Franklin, WI
 (US)

(73) Assignee: **TABLECRAFT PRODUCTS
 COMPANY**, Gurnee, IL (US)

(**) Term: **14 Years**

(21) Appl. No.: **29/461,866**

(22) Filed: **Jul. 29, 2013**

(51) LOC (10) Cl. **07-06**

(52) U.S. Cl.

(57) **CLAIM**

The ornamental design for a dispenser, as shown and described.

DESCRIPTION

FIG. 1 is a rear perspective view of a dispenser showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom view thereof.

The broken lines shown in the figures represent portions of the dispenser that form no part of the claimed design.
